UNITED STATES PATENT OFFICE

JOHN BRANDWOOD, OF SOUTHPORT, ENGLAND

YARN BEAM

Application filed January 15, 1926. Serial No. 81,561.

The treatment with dye or analogous liquors of yarns wound on beams by the passing of the said liquors through the yarns and through the body of the beam has great and 5 commercially recognized advantages as to saving of time and cost, over the old method of skein dyeing analogous treatment; and also, when there is a sufficiency of the yarn to be dyed, over the method of dyeing the yarn 10 in cheeses or like packages and then winding upon a beam for subsequent handling. It often happens however that the quantity of yarn to be dealt with is not sufficient to fill a treatment beam of full size and is too great 15 for economical handling by the cheese treatment methods. Skein dyeing is then resorted to, with the unavoidable disadvantage of the extra costs, entailed by that method over the beam treatment method.

20 The object of this present invention is to provide means whereby yarn in quantities less than that required to fill an ordinary full sized beam, for treatment thereon, may be wound as required and then dyed or otherwise treated in the same manner and by the same means as a full size beam. According to the said invention section beams are employed to any desirable number and of any desired width between flanges, with means 25 for assembling a plurality of such section beams into a complete beam, and means for ensuring that all fluids with which the yarns on the said section beams are to be treated shall pass through the yarns only in the treatment vessel.

30 A very convenient method of carrying the invention into effect will now be described, it being understood that the details given may be varied without departing from the 35 spirit of the invention.

In the drawings:—

Figure 1 is an end elevation of a section beam showing the flange and a method of securing one type of yarn bearing surface within 40 the end flanges;

Figure 2 is an elevation partly in section of the section beam shown in Figure 1;

Figure 3 is a sectional view showing the 45 end flanges of adjacent section beams when placed together;

Figure 4 represents the extreme end flanges forming the flanges of a complete beam composed of a plurality of section beams, showing the means for converting the beam into a homogeneous whole for the purpose of handling and treatment;

Figure 5 is an elevation, partly in section of a full size beam composed of a plurality of section beams of varying widths; Figure 6 is an elevation (broken) partly in section 55 of a filler or dummy beam; and

Figure 7 is an elevation of an assembled beam consisting of a plurality of section beams one of which is a dummy section beam.

Referring to Figures 1 and 2, 6 are end flanges each of which as to its outer portion is composed of non-corrodible metal of convenient thickness, nickel or a nickel alloy may be used. The inner portion of each flange is composed of a ring of cast metal 7 having 60 the strengthening arms 8, the central bore 9 for the reception of a shaft, circular bosses 10 bored for the reception of further shafts. The edge of each ring is returned outwardly 65 as at 11, thus forming an angle ring, and the outer peripheries of the rings so formed are slotted on a radius as at 12. Each slot 12 is of just sufficient width to allow of a strip 70 of non-corrodible metal 13 to be pushed thereinto with a tight push fit. Intermediate of the end flanges is the supporting ring 14 which is slotted in a similar manner to the flange rings 7 to receive the metal strips 13. The supporting ring 14 is provided with 75 the bosses 15 registering with the similar 80 bosses 10 of the flange rings 7, and through these bosses on the flange rings and intermediate supporting ring are passed tubular shafts 16, which are threaded at their extremities to receive nuts 17. The ring 14 may be maintained in the position longitudinally of the beam in any convenient manner, for instance by means of set screws passing through bosses 85 and engaging the tubular shafts. The outer flange portions 6 of nickel or the like, which 90 are annular, have their inner peripheries returned as at 18, and the angle rings 7 are secured within these returned flanges 18 by the rivets 19.

100 It is essential, to ensure that when two sec-

tions are in place together, there should be no passage for fluids between adjacent flanges, as treatment by fluids under pressure is contemplated and all fluids must pass through the yarns only to the interior of the beam, or in the reverse direction, in the known manner of treating full sized beams of yarn. A convenient method of making a fluid tight joint is shown in Figure 3. One angle ring 7 of each section has the inner face of its peripheral flange 11 recessed as shown at 20, and the other angle ring 7^a is recessed on the outer face of the peripheral flange as shown at 21. When two section beams are placed together, therefore, a rabbet joint is formed which, the recesses being machined and faced up, will under pressure form a fluid tight joint.

Various section beams sufficient to form a complete beam length having been wound, these section beams—five various widths are shown in Figure 5—are taken and a central shaft 22 Figure 5 is passed through the central bosses 9. Rods 23 of a non-corrodible metal such as Monel metal, are then passed through the tubular shafts 16 of the section beams, these rods being threaded at their extremities to receive the nuts 24, as seen in Figure 4. In this figure the metal strips 13 are omitted for clearness. By screwing up the nuts 24 therefore the adjacent flanges of section beams are pressed tightly together and the plurality of section beams are for practical purposes transformed into a single beam for handling and treatment in a treatment vessel, such as the kier described in the specification to United States Letters Patent No. 1,174,662. It will be noted that owing to the form of the flange rings 7, the end flanges of the completed composite beam will always have a tubular boss to fit within a seating of a vessel such as that described in the prior specification just referred to, whilst it may be maintained in position by the screw also described in that specification, the central shaft 22 of course being removed.

The weight of yarn on each section beam is of course much less than the weight of yarn wound on a complete single unit full size beam, and it is considered unnecessary therefore to provide a strong cast iron or like backing for the nickel or like flange portions. Nevertheless where it is thought desirable such backings may be provided, as they will not come into contact with the yarns. Where the nickel or like outer flange portion only is employed, the periphery of such flange may be turned over as shown at 25 Figure 4, to present a greater surface for support of the edge when it is for instance rolled, to prevent distortion of the plane of the flange.

The section beams which go to form a complete composite beam need not be of equal widths between flanges. They may be of varying widths to receive a greater or smaller

weight of yarn, as in Figure 5. Any overall widths or combination thereof, suitable to make up the length of a full sized beam may be adapted. Where the length of a section beam makes it desirable, extra supporting rings may be provided between the flanges or the ring may be omitted. Two of these are shown in the section beam on the right of Figure 5; the next in position has one; whilst the remaining two sections being comparatively narrow, do not require these intermediate supports.

Any convenient and suitable means for winding section beams for the purpose of the invention may be employed, for instance the known sectional warping frame or the ordinary full beam warper. If the latter is employed the usual winding drum is removed and winding effected by means of the apparatus described in the specification of application for United States patent filed under Serial No. 32,513. By the latter method a number of sections may be wound simultaneously, when connected together. At those points where flanges and angle rings occur in the length of such a composite beam, the dents in the comb of the warping frame which are opposite to the said flanges and rings are of course left blank.

After treatment of the yarns, the composite beam may be handled in any desired manner, or the said beam disassembled for the handling of each section beam separately.

It is not essential for the purposes of this invention that the yarn bearing surface of a section beam should be formed of strips of metal as shown in Figures 1, 2 and 5. The construction of a beam such as described in the specification to United States Letters Patent No. 1,125,803 may of course be followed, with the necessary modification where necessary as to the structure of the flanges.

In addition to the advantage of enabling various section beams to be wound with a less number of ends of yarn upon each than would be necessary to fill a full beam, with subsequent treatment of a plurality of such section beams together, the invention can be employed for the purpose of treating a number of section beams which, in their total length when placed together as hereinbefore described, would fall short of the length of a complete and single unit beam. Where the number of section beams wound with yarn is not sufficient to form, when such section beams are placed together, a complete beam of a sufficient length for treatment in a desired vessel as for instance the kier of United States Letters Patent 1,174,662, fillers or dummy sections may be employed to make up the necessary length, and a convenient form of such a filler or dummy is illustrated in Figure 6. In that figure, 26 is an angle ring which with the exception of the radial slots 12 may be of the same form and construction

as the angle rings hereinbefore described and indicated at 7 in the drawings Figures 1, 2, 3 and 4. The surface of the dummy beam is composed of an imperforate cylinder 27 of metal open at the ends and riveted to the angle rings as shown in Figure 6. The flanges 6 are omitted as being unnecessary but as shown in the Figure 6 the means for making a tight joint with an adjacent section beam flange are provided on the angle

10 rings. The position of one such dummy section in its relation to the yarn bearing section beams, in a complete assembled beam, is shown in Figure 7.

15 By using more of these fillers therefore as may be required or only one of the length required the full length of a complete beam may be made up for treatment, whilst the imperforate surface of the cylinder 27 effectually 20 prevents the passage of fluids other than through the yarns on the adjacent section beams when a filler or fillers is or are assembled with such section beams.

In the form of dummy beam illustrated 25 tubular shafts 16 are provided as in the section beams for the passage of the tie rods 23 therethrough.

I claim:

1. A section beam on which yarns are to 30 be wound for the subsequent treatment of the said yarns with fluids upon the said section beam, comprising annular end flanges, a yarn bearing surface permitting the passage of fluids therethrough, an angle ring within 35 each annular end flange which angle ring forms a tubular boss for the section beam flange, a recess on the upper face of one of the angle rings, these recesses being respectively one half of a rabbet joint, and means 40 for allowing to pass through the section ring a device on which a plurality of the section beams may be mounted and secured together flange to flange.

2. A section beam on which yarns are to 45 be wound for the subsequent treatment of the said yarns with fluids upon the said section beam, comprising annular end flanges, with tubular bosses, a yarn bearing surface permitting the passage of fluids therethrough, 50 means for forming a fluid tight joint upon the outer face of each of the flanges and around the central opening thereof, and tubular shafts connecting the two end flanges together and open at their ends to receive 55 rods upon which a plurality of the section beams may be mounted and secured together flange to flange.

3. A section beam on which yarns are to 60 be wound for the subsequent treatment of the said yarns with fluids upon the said section beam, comprising annular end flanges, an angle ring secured within each such end flanges, which angle ring forms a tubular boss, a yarn bearing surface composed of 65 metal strips held in position by radial slots

upon the said angle rings, a recess formed on each angle ring each such recess being the half of a rabbet joint, and tubular shafts connecting the two angle rings and thus the two end flanges together, the tubular shafts being 70 screwed in position in the angle rings but open at their ends to receive rods upon which a plurality of the section rings may be mounted and secured together flange to flange.

4. A plurality of section beams each of which is provided with annular end flanges and a yarn bearing surface permitting the passage of fluids therethrough, the said sections being placed flange to flange, a tubular 80 boss formed on each end flange the upper face of one such boss being recessed and the lower face of the other such boss being recessed, members passing through the plurality of section beams, and means upon the said members for pressing the section beams tightly together in the direction of the length of such members and to detachably hold the beams in that position, the recesses on the tubular bosses forming parts of a fluid tight joint.

5. A plurality of section beams each of which is provided with annular end flanges, a yarn bearing surface permitting the passage of fluids therethrough, the said section beams being placed flange to flange, a fluid tight 90 joint formed by adjacent flanges, and around the central openings thereof, tubular shafts connecting the two flanges of each such section beam together to maintain them in relative position, the ends of such shafts being 95 open, and rods passing through the said tubular shafts of each of the plurality of section beams, which rods are provided with screw means for pressing the section beams tightly 100 together flange to flange.

6. A plurality of section beams each of which is provided with annular flanges, an angle ring secured within each flange which angle ring forms the tubular boss of such flange, radial slots in each angle ring to receive metal strips forming the yarn bearing surface of the beam, tubular shafts connecting the angle rings and thus the end flanges of each section beam together, such tubular shafts being open at their ends, and rods passing 110 through the tubular shafts of each of the plurality of section beams, a fluid tight joint between adjacent flanges of adjacent section beams, and around the central openings thereof, threaded extremities upon the said rods, and nuts upon such threaded extremities to press the plurality of section beams 120 tightly together flange to flange upon such rods.

7. A plurality of section beams each of 125 which is provided with annular end flanges and a yarn bearing surface permitting the passage of fluids therethrough, a dummy section beam provided with annular end flanges and having an imperforate cylindrical sur-

face, the said section beams and dummy section beam being placed flange to flange, a fluid tight joint formed by adjacent flanges and around the central opening thereof, members passing through the plurality of section beams and the dummy beam, and means upon the said members for pressing the section beams and the dummy beam tightly together flange to flange in the direction of the length of said member and to detachably maintain them in that position.

8. A plurality of section beams each of which is provided with annular end flanges and a yarn bearing surface permitting the passage of fluids therethrough, a dummy section beam provided with annular end flanges and an imperforate cylindrical surface, the said section beams and the dummy beam being placed flange to flange, a fluid tight joint formed by adjacent flanges and around the central openings thereof, tubular shafts connecting the two flanges of each such section beam together, tubular shafts connecting the two flanges of the dummy beam together, the ends of such shafts being open, and rods passing through the tubular shafts of each of the plurality of section beams and of the dummy beam, which rods are provided with means for pressing the section beams and the dummy beam tightly together flange to flange and to detachably maintain them in that position.

In testimony whereof I have hereunto set my hand.

JOHN BRANDWOOD.
